UNITED STATES PATENT OFFICE.

BENJAMIN E. LINFOOT, OF PHILADELPHIA, PENNSYLVANIA.

BOTTLE CARRIER AND CONVEYER.

1,242,825.

Specification of Letters Patent.

Patented Oct. 9, 1917.

Application filed January 11, 1917. Serial No. 141,800.

To all whom it may concern:

Be it known that I, BENJAMIN E. LINFOOT, a citizen of the United States, residing in the city and county of Philadelphia, 5 State of Pennsylvania, have invented a new and useful Bottle Carrier and Conveyer, of which the following is a specification.

My invention consists of a carrier and conveyer for bottles to be washed, soaked, 10 or otherwise cleansed in which certain members of the device are vastly strengthened and simplified in construction, and other novel features are presented, as will be hereinafter fully set forth.

15 The invention is satisfactorily illustrated in the accompanying drawing, but the important instrumentalities thereof may be varied, and so it is to be understood that the invention is not limited to the specific 20 details shown and described.

Figure 1 represents a plan view of a bottle carrier and conveyer embodying my invention.

Fig. 2 represents a longitudinal section 25 thereof.

Fig. 3 represents a transverse vertical section on line 3—3 of Fig. 1.

Fig. 4 represents a perspective view of one 30 of the supporting columns employed.

Fig. 5 represents a perspective view of the bottom member of the frame of the 35 device.

Similar numerals of reference indicate corresponding parts in the figures.

35 Referring to the drawings:—

1 designates the top of the frame of the device, the same being depressed at intervals forming the conical openings 2 for bottles, as will be hereinafter more fully explained.

40 3 designates the bottom of the frame of the device, the same having struck up at intervals, the tubular collars 4 which telescopically receive and guide the tubular movable sleeves 5, whose upper portions are 45 flaring and provided with inturned shoulders or necks 6, on which the mouths of bottles inserted in the openings 2 may be rested, said sleeves 5 being sustained on the coil springs 7 which surround said sleeves

50 and the collars 4 and are supported on the bottom 3 and bear upwardly against the flanges 8 on the upper ends of the sleeves 5, whereby the latter are resiliently sustained on said springs and are adapted to yield 55 downwardly when the sleeves are subjected to pressure from above.

Attention is drawn to the fact that a primary holder for the bottles is placed above the openings 2, a form of which is shown in the Letters Patent No. 1,171,128, 60 granted to me on the 8th day of February, 1916, but to which I do not limit myself, it being noticed that when the bottles in inverted position are placed in the holder their mouth pieces are inserted through the 65 openings 2 and rested resiliently on the necks 6 as cushions, whereby they are prevented from breaking and should the bottles be of different and greater lengths, the sleeves 5 will yield downwardly and so accommodate themselves to such bottles. In this condition of affairs the device with the holder is introduced into a washing machine or soaker for the bottles, so as to cleanse the latter. 70

Attention is directed also to the fact that the collars 4 are integral with the bottom 3, and the latter forms a continuous piece of metal or material throughout the length of the frame, thus simplifying the construction of said bottom. Furthermore, said sleeves are within said collars, so that the joints of the collars and sleeves are on the exterior of the sleeves, leaving the latter and said collars unobstructed throughout 85 their length and preventing the water from leaking downwardly in said joints.

The top and bottom of the frame are connected by the bolts 9 which extend vertically through said top and bottom and are 90 tightened by the nuts 10, and through heads or columns 11 of metal or other suitable material, they being interposed at intervals between said top and bottom and held tightly in contact with the same, they having tube like members 12 therein to receive said bolts 9, and being made hollow for purpose of lightness and inexpensiveness. 95

Rising from the sides of the bottom 3 of the frame are the walls 15 which comprise portions of the sides of said frame. Bearing against said walls are the arms 13 which depend from the sides of the top 1 of the frame and are upturned from below forming the loop-shaped members 14 which 100 bear resiliently against said walls causing the latter to press against the columns or heads 11 and assist in retaining them in position, said members extending longitudinally along the frame, as shown by the 110 dotted lines Fig. 1, serving also to strengthen the sides of the top of the frame.

Having thus described my invention what I claim as new and desire to secure by Letters Patent, is:-

1. In a bottle carrier and conveyer of the character stated, a frame composed of a top and bottom, and means for connecting the same, said top having therein openings for the inlet of the mouth of a bottle, a resilient tubular support for the bottle below said openings, and a tubular collar rising from said bottom, said support being telescopically fitted to said collar on the interior thereof.
2. In a bottle carrier and conveyer of the character stated, a frame composed of a top and bottom, said top having therein a series of openings, a column-like member interposed between said bottom and top, means for securing said top and bottom to said member, a series of collars rising from said bottom, a sleeve pending from the wall of said opening, and means for resiliently sustaining said sleeve in normal position, said collar telescopically containing said sleeve within the same.
3. In a bottle carrier and conveyer of the character stated, a frame composed of a top and bottom, and means for connecting the same, and a column-like member interposed between said bottom and top and secured thereto, said top having on its side

a resilient member continuous thereof adapted to bear against the side of said column-like member.

4. In a bottle carrier and conveyer of the character stated, a frame composed of a top and bottom, said top having an opening therein, a collar rising from said bottom, and a resiliently-supported sleeve telescopically fitted in said collar, a column-like member interposed between said top and bottom adapted to sustain said top, and means in said member secured to said bottom and top for clamping together said top, bottom, and column-like member.

5. In a bottle carrier and conveyer of the character stated, a frame composed of a top and a bottom, means interposed between said bottom and top for sustaining the latter and clamping the same with the interposed means, a series of openings in said top, a series of collars rising from said bottom, and a series of resiliently-supported sleeves telescopically fitted in said collars and extending downwardly from the walls of said openings, said bottom being continuous from collar to collar, and said collars being integral with said bottom.

BENJAMIN E. LINFOOT.
